A. K. RIDER.
VALVE GEAR FOR STEAM ENGINES.

No. 66,392.

Patented July 2, 1867.

A. K. RIDER, OF NAZARETH, PENNSYLVANIA.

Letters Patent No. 66,892, dated July 2, 1867.

IMPROVEMENT IN VALVE-GEAR FOR STEAM ENGINES.

The Schedule referred to in these Letters Patent and making part of the same.

TO ALL WHOM IT MAY CONCERN:

Be it known that I, A. K. RIDER, of Nazareth, in the county of Northampton, and State of Pennsylvania, have invented certain new and useful improvements on Steam and other Engines, of which the following is a full, clear, and exact description, reference being had to the accompanying drawings, forming part of this specification, and in which—

Figure 1 represents a sectional side elevation of a steam engine embracing my improvement, and constructed as applicable to drilling or channelling purposes.

Figure 2 is a horizontal section through the line xx in fig. 1.

Figure 3, a vertical section through the line yy in fig. 1, and

Figure 4 an end elevation or outside view at right angles to figs. 1 and 3.

Like letters indicate like parts throughout the several figures.

My improvement relates to that system of operating the piston of an engine in which a duplicate arrangement of valves is used, the one that may be termed a sub-valve being worked by the engine to admit and exhaust steam to operate or throw the other or main valve to the engine cylinder, and the nature of my invention, which includes a novel mode of varying the speed or force of the piston within the engine cylinder, consists in a combination, with the engine piston or valve controlling its motion, of a regulator so constructed and operating as either to vary the length or position, or both, of the valve stroke in such a manner as that not only may a heavier or lighter stroke be given to the engine piston, but its force in one direction made greater at pleasure than in the other, the same being effected automatically on adjustment of the regulator. The invention also consists in a peculiar construction of valve-regulator, likewise in a novel construction of engine cylinder, valve, and combination of main and sub-valve having a common inlet and exhaust. Also said invention consists in a novel combination of means for operating the sub-valve, and furthermore, in a combination of sub-valve, main valve, and regulator controlling in a novel manner the action of the latter.

Referring to the accompanying drawing, A represents the cylinder (here shown vertical) of the engine; B its piston; and C, the piston-rod, which, in the present instance, is arranged to run through the top of the cylinder or its cover. Connected with the upper end of the piston-rod is an arm, D, that may have attached to it a vertically sliding bar, E, which may form the drill-stock or holder, or the arm may have connected with it a clamp for, by or in connection with securing screws, carrying a series of stocks or drill-holders, as necessary in channelling operations. This sliding-bar E may be guided by and work in contact with a fixed vertical support, F. G is the main valve working in a cylinder, H, and made up of pistons or rings $a a'$ and $b b'$, forming spaces or chambers $c c'$ and d between them, the two outer chambers $c c'$ being constant or fixed steam spaces, to which steam is supplied by passages $e e'$, and from which it is passed alternately by passages $f f'$ to the upper and lower ends of the cylinder to reverse the action of the engine piston. The chamber d is an exhaust-steam space in constant communication with an exhaust outlet, I, and into or through which the steam is exhausted from opposite ends of the engine cylinder alternately. This alternate inlet and outlet action to opposite ends of the engine cylinder is produced by the shooting or working of the valve G, to which S is the rod or stem, so as to bring the passages $f f'$ in communication with their respective steam-chambers c and c' , or their general exhaust d . The pistons, disks, or rings $a a'$ and $b b'$ should be situated sufficiently apart to insure this action of the valve G under a wide or varying range of throw, that is, that it will so operate both, whether its throw be long or short, or longer in the one stroke than the other, changing its altitude or position of travel to vary the action of the piston, and which is produced by a regulator connected with said valve, as will be hereinafter described. The valve G is operated or thrown by the direct agency of the impelling fluid, as controlled by a sub or auxiliary valve, J, which is worked automatically by the engine. This valve J is also shown as made up of pistons h , one at either end, working in a cylinder, K, the space or chamber i between said pistons forming a fixed or constant steam space to which steam is admitted by a passage, j , from a chamber or space, L, connecting with the main steam inlet M, said chamber L also serving to supply, by the passages $e e'$, the main valve-cylinder or spaces $c c'$ with steam. $k k'$ are passages to convey the steam from the chamber i of the sub-valve to above or below the main valve G to shoot or throw it accordingly as the sub-valve is worked to put the ports k or k' in communication with the steam-chamber i , or by spaces above and below the pistons of the sub-valve, with an upper and lower exhaust passage or passages $l l'$, connecting by an opening, m , with the exhaust-chamber d of the main valve in constant communication, as before specified, with the general exhaust I.

To thus alternate the throw of the main valve, the sub-valve J is or may be operated as follows: Attached to the arm D of the engine piston is a block, N, preferably made adjustable in a vertical direction, and serving on the ascent of the engine piston to lift a lever, O, which, pressing on the under side of a nut, n , on the sub-

valve shaft *g*, lifts the latter till a lower nut, *o*, on the rod *g*, rides over and rests on a rest, *p*, to one side of a detent-lever, *P*, pivoted, as at *q*, the front of the rest *p* inclining upward to facilitate the riding of the nut *o* over and on to its top. This lift and rest of the sub-valve allows steam to flow by the passage *k* into the cylinder *H* to act upon the top of the main valve *G*, and shoot it downward, at the same time opening the passage *k'* to the exhaust, which removes pressure from the under face of the main valve. The downward movement of the main valve *G* opens the lower portion of the cylinder *A* by the passage *f'* to the exhaust-chamber *d*, and the upper portion of said cylinder, by the passage *l* to the steam-chamber *c* of the main valve, which induces a downward action of the piston *B*. At or towards the close of the descent of the engine piston, the detent-lever *P* is tripped, causing the nut *o* of the valve-rod *g* to be released from its support on the rest, when a spring, *r*, shoots down the sub-valve and suddenly changes its action, so far as controlling or reversing the main valve, which is then lifted by steam being admitted below it, and exhausted from above it, and the movement of the engine piston changed to an upward one by the passage *f'* being opened to the steam, and the passage *f* to the exhaust. The sub-valve thus shot downward is held or locked in such position by the pressure of the spring *r*. The detent-lever *P* is or may be tripped in the descent of the engine piston to allow of the nut *o* passing the rest *p* by the nose *s* of a spring-held plate or lever, *Q*, pivoted, say as at *t*, to the arm *D*, striking and bearing down or away on an inclined projection *u* of the detent-lever, which, however, may be otherwise tripped.

Having now specified how the valves are or may be operated, I will proceed to describe the action of the regulator, which serves not simply to govern the throw of the main valve *G*, as regards its length of stroke, which of course regulates the quantity of steam admitted to act on the engine piston, but also acts to vary the supply of steam to—in a double stroke—opposite sides of the engine piston, by which double regulation not only may the speed of equal engine strokes be increased or diminished, but the up or down force or intensity of action of the engine piston be changed, and a light up and heavy down stroke, or *vice versa*, be given. In this way may the force of the blow be adjusted, both by varying the speed of the engine piston and by supplying different quantities of steam for the up-and-down stroke of the latter. The regulator which accomplishes this may be constructed as follows: Attached to the rod *S* of the main valve by, say, a connecting-bar or link, is a wedge-shaped lever, *R*, pivoted, as at *v* to an arm, *T*, that may be stationary, and which, spreading at its outer end, is provided at such part with a curvilinear slot *u*. Between the fixed arm *T* and wedge-shaped lever *R* is a slotted horizontally sliding bar, *U*, rocking say on the pivot *v*, and held at any desired position in or out or up or down by a locking-screw, *w*, passing through the slot *u*. This rocking and horizontally sliding bar *U* carries intermediately of its length a slotted clip or stop-bar, *z*, through which the lever *R* passes. To secure an equally forcible stroke in both directions of travel of the engine piston, it is only necessary to adjust the bar *U* in a horizontal position, or midway of the slot *u*, when the throw of the main valve as regulated by the lever *R*, and clip or stop-bar *z*, will be equal in both directions as regards its control of the ports or passages which it opens and closes. To regulate the amount of such equal throw it is only necessary to work in or out and set the bar *U* so as to cause the wedge-shaped lever *R* to strike sooner or later the clip or stop-bar *z*, while to vary the altitude in travel of the valve, so as to make it open and close unequally the top and bottom ports or passages to the engine cylinder, in order to admit more steam in one direction of travel than the other, it is only requisite to rock and set up or down the bar *U* accordingly as more steam is required above or below, the adjustment of the clip or stop-bar *z* up or down determining the altitude in travel of the valve or its action relatively to the engine ports or passages, so as to close or open one to a greater extent than the other.

Not only may such a mode of regulating the stroke or force of the engine piston be employed to advantage in drilling and channelling operations, but in a variety of work. When used to operate a direct-acting hammer, the engine piston-rod should project through the lower end of the cylinder. For pumping purposes, instead of the percussion arrangement described for operating the sub-valve, simple tappets may be used. The same action of valves, as has been here described, may be produced by reversing the inlet and outlet passage or passages, that is, exhausting where admitting steam, and *vice versa*. In speaking of steam, such is only done by way of illustration, the operation being the same when a different impelling fluid is employed.

What I here claim as new and useful, and desire to secure by Letters Patent, is—

1. The combination, with the reciprocating piston *B* and the main valve controlling the same, of a regulator so constructed and operating as not only to admit of the valve stroke being lengthened or shortened to change the speed or force of engine strokes, but also of being so varied in position relatively to the engine cylinder's ports as to secure when required to the engine piston a more forcible stroke in one direction than the other, substantially as specified.

2. The regulator to the engine cylinder-valve arranged and operating substantially as described.

3. The arrangement of the sub-valve *J*, relatively to the main valve *G*, the one being controlled by the other, as specified, when said valves have a common inlet and exhaust, and are otherwise arranged for operation together, substantially as specified.

4. The combination of the arm operated by the engine piston, of the block *N*, lever *O*, spring *r* to the sub-valve *J*, lever *S*, and detent-lever *P* operating in connection with the rests, lifting nuts or stops to operate the sub-valve, as herein described.

5. The combination with the engine piston of a sub-valve operated thereby; main valve controlled by the sub-valve, and regulator governing the action of the main valve, essentially as and for the purpose or purposes herein set forth.

A. K. RIDER.
